CLAIM

The ornamental design of a container for plumb bob string, as shown and described.

DESCRIPTION

FIG. 1 is a front perspective view of a container for plumb bob string showing my new design;

FIG. 2 is a front elevational view thereof;

FIG. 3 is a right side elevational view, the left side elevational view being a mirror image;

FIG. 4 is a top plan view thereof;

FIG. 5 is a bottom plan view thereof;

FIG. 6 is a back elevational view thereof; and,

FIG. 7 is a front elevational view of an embodiment of FIGS. 1-6 showing my new design thereof.

FIG. 1FIG. 2FIG. 3FIG. 4FIG. 5FIG. 6FIG. 7
